UNITED STATES PATENT OFFICE.

WALTER I. HEY AND ZELL L. COFFIN, OF ARDMORE, SOUTH DAKOTA.

MATCH-LIGHTER.

1,132,342.

Specification of Letters Patent. Patented Mar. 16, 1915.

Application filed August 8, 1913. Serial No. 783,816.

To all whom it may concern:

Be it known that we, WALTER I. HEY and ZELL L. COFFIN, citizens of the United States, residing at Ardmore, in the county of Fall River and State of South Dakota, have invented new and useful Improvements in Match-Lighters, of which the following is a specification.

This invention has relation to match 10 lighters and it consists in the novel features hereinafter described and claimed.

The object of the invention is to provide a match lighter of simple structure which includes a plate adapted to support a material having a rough surface so that the rough surface is protected when the article is attached to the clothing of a wearer and at the same time the said roughened material is exposed so that a match may be 20 readily struck against the same.

A further object of the invention is to provide in a match lighter of the character indicated, means for permitting the material to be renewed when desired, the said 25 means being so disposed as to not interfere with the support of the material upon the plate when in use.

Another object of the invention is to provide a pin or securing means for a match 30 lighter as indicated.

In the accompanying drawings—Figure 1 is a perspective of the match lighter. Fig. 2 is a longitudinal sectional view of the same, and Fig. 3 is a transverse sectional 35 view of the same.

The match lighter comprises a metallic plate 1 which is preferably rectangular in configuration. This plate is provided with curled edge portions 2. The plate is provided 40 in its intermediate portion and in the vicinity of one end and under one of the curled portions 2 with a slot 3. The inner sides of the curled portions 2 are spaced from the surface of the intermediate portion of the plate. A pin 4 is hingedly mounted upon the back of the plate and its free end is adapted to engage a keeper 5 also mounted upon the back of the plate.

A strip of material 6 having a roughened 50 outer surface is located against the intermediate portion of the plate and is bound around its edges by the curled portions 2 of the plate. The transverse breadth of the

material 6 is no greater than the length of the slot 3 while the area of the said material 55 is greater than the area of the space between the edges of the curled portions 2 of the plate 1 so that the said material when in position is secured upon the plate around all of its edge portions. 60

In use, the pin 4 is passed through the fabric of the garment and the garment may be swung with one hand to bring the roughened surface of the material 6 to an exposed position. With the other hand, an operator 65 may then strike a match against the roughened surface of the material 6 whereby the match is ignited. When the material 6 has become worn or unfit for use, the strip may be readily withdrawn through the slot 3 by 70 bowing the intermediate portion of the material in order to bring one edge of the material opposite the said slot. After the worn strip has been withdrawn from between the curls 2 of the plate 1, a new strip may be 75 inserted in position in lieu of the strip just removed.

Having described the invention what is claimed is:

A match lighter comprising a metallic 80 plate of rectangular configuration having at its edges inwardly curled portions, the inner surfaces of which are spaced from the surface of the intermediate portion of the plate, said plate being provided in the vicinity of one end and under one of the said curled portions with a slot which extends transversely across the plate, said slot being spaced from the outer portion of the adjacent curl, the ends of the said slot being 85 under the curled portions at the opposite sides of the plate, and a strip of material having a roughened surface located between the intermediate portion of the plate and the said curled portion, the said strip being of a greater area than the space between the edges of the curled portion and the material being less in transverse breadth than the length of the slot. 90

In testimony whereof we affix our signature in presence of two witnesses.

WALTER I. HEY.
ZELL L. COFFIN.
